BRADFORD B. HOLMES, OF NEW YORK, N. Y.

REFRIGERATING APPARATUS.

Application filed February 26, 1920. Serial No. 361,404.

To all whom it may concern:

Be it known that I, BRADFORD B. HOLMES, a citizen of the United States, and resident of New York city, in the county of New York 5 and State of New York, have invented certain new and useful Improvements in Refrigerating Apparatus, of which the following is a specification.

My present invention relates to refrigerating apparatus of the type wherein a volatile liquid is evaporated to absorb heat thereby producing the desired refrigerating effect, the volatilized gas is re-liquefied by compression and cooling, and the condensed liquid is returned to the evaporating chamber to be again evaporated, in continuously repeating cycle.

The arrangement is such that the only joints are around relatively large openings 20 and these are closed by relatively massive parts having ample contact surfaces rigidly bolted together so that, with the low pressures employed, development of leaks is practically impossible. Moreover, an important feature of my invention is a novel arrangement for transmitting power from the exterior motor to the compressor through a wall of the condensing chamber, without using any stuffing box or packed joint such 30 as is commonly employed to prevent leakage where there is a rotary shaft or other driving element having moving engagement with an opening through the wall of a pressure chamber.

I accomplish this by employing a flexible closure secured gas-tight over an opening through the wall of said condensing chamber. Secured gas-tight in a movable portion of said flexible closure is a power transmitting member the power transmitting movements of which flex said closure but do not require rotation of said member.

I employ a flexible tubular member which will give sufficient resistance against the internal gas pressure and against any tendency for the tubular member to be rotated by the motion transmitting device. If very flexible, the tubular member will be extended outside of the condensing chamber so as to be distended by the gas pressure applied from within. Preferably, however, it will be of sufficient radial stiffness to withstand the pressure when applied on the outside thereof, and, in such case, the tube may project 55 into the condensing chamber. The latter ar-

rangement is of advantage since a tube stiff enough to withstand the external pressure must usually be quite long in order to have sufficient lateral flexibility.

The flexible tube which I prefer to use for this purpose is a well known form of thin metal tubing having deep flat-sided corrugations. These corrugations may be circular as in tubes now obtainable in the market or they may be helically disposed after the manner of a screw-thread of slight pitch.

Where considerable pressures are employed and particularly where the tube is of considerable length as in my present device, internally applied pressure operates to produce unequal, longitudinal curvature of the walls thereby subjecting the metal of the walls to undesirable initial tension stresses on one side of the tube and corresponding compression stresses on the other side, whereas, externally applied pressure tends to straighten the tube if curved and to resist local flexing efforts. Hence, there is peculiar utility and advantage in employing this type of flexible tube as a flexible closure projecting into the condensing chamber rather than outwardly therefrom.

In order that the crank shaft may be properly supported within the flexible tube, I prefer to arrange an overhung bearing sleeve projecting from a plate which may be bolted over the opening around which the flexible tube is clamped and sealed as above described.

The above and other features of my invention may be more fully understood from the following description in connection with the accompanying drawings, in which

Figure 1 is a vertical section along the axis of the machine;

Figure 2 is a cross section on the line A—A, Figure 1;

Figure 3 is a perspective sketch of the motor and vanes of the compressor; and

Figure 4 is a sectional detail of a modified form of crank transmission.

In Figure 1 the device is shown as mounted on a portion of a refrigerator 10 which may be of any known or desired construction. The mounting comprises a base 11 which may be a metal casting on which is rigidly mounted the electric motor 12 and a condenser chamber 13. The motor may be of any known or desired construction affording the required power—one-quarter

- horse power or more according to the size of the machine. The condenser 13 is a casting preferably of copper so as to be of high heat conductivity. It is cast, machined, or 5 otherwise provided with numerous longitudinal ribs 14, projecting from its outer surface. It is preferably surrounded by a casing 15 which may be of sheet metal and which preferably contacts with the outer 10 edges of the ribs to form longitudinal passages for flow of the cooling air. An air draft through these passages is maintained by fan 16 on the shaft of motor 12 thus cooling the condenser.
- 15 Within the condenser and attached to the end plate 17 is the compressor. This is preferably a rotary force pump comprising the rotor 18 and blades 19 which revolve within the hardened steel cylinder 20 and the end 20 plates 21 and 22 which carry the ball bearings on which the rotor revolves. The blades 19 are of hardened steel and contain grooves 23 on their side edges. The slots in the rotor 18 into which the blades fit are machined 25 clear through so that the rotor consists of 4 separate quarter cylindrical elements held together by the shoulders 24.

Casing 20 contains a suction port 28 which communicates with space 26 in the evaporator 29 by the passage 30 shown in dotted lines; also a discharge port 31 which discharges into the condenser 13 in such a manner that the compressed gas containing a small amount of glycerine which has leaked 35 by the clearances in the pump, is blown out through ball bearings 32 and 33, serving to lubricate them.

The blades 19 are yieldingly pressed outward against the inner surface of casing 20 40 by centrifugal force and are in effect rotary pistons dividing the pump cylinder in four chambers of cyclically increasing volume, sucking gas on the increase of volume and compressing it on the decrease in the well 45 known way.

A small hole 25 is drilled lengthwise through the outer shaft of the pump and communicates with the evaporator space 26 and also by passage 27, with the bottom of 50 the condenser. The condenser contains a certain amount of glycerine for lubricating purposes, and owing to the fact that when the pump is in rotation, the axial space is under less pressure than exists in the condenser, the glycerine will be forced via passages 27, 26, and 25 into the rotor of the pump where it will seal the clearances between blades 19 and rotor 18, fill grooves 23 and generally act as a lubricant for the 55 pump and a liquid seal on the pump clearances.

It will be noted that the entire pump assembly can readily be removed from the condenser 13 by removing plate 17.

65 Power from the motor is applied to the

pump in the following manner. A plate 34 is bolted gas tight to the condenser 13 opposite to plate 17. This plate 34 has secured to it by soldering, brazing or other suitable means, a flexible tube 35. As before explained, this tube may be a thin walled metal tube circularly or helically convoluted so as to be extremely flexible. It may be a plastic or other flexible composition or the plate 34 could be made as a flexible diaphragm. I 75 prefer to use, however, the flexible circularly or helically convoluted tube which is an article in general use. At the inner end this tube is sealed gas-tight to the non-rotating power-transmitting member 36. The shaft 37 has a 80 crank 38 at its end, the centerline of the crank being along the line B B. Rotation of the shaft 37 and crank 38 transmits to piece 36 through the ball bearing 39 the above described non-rotating circular motion which 85 for want of a better name may be called oscillatory.

Piece 36 has crank 40 attached to it which moving in a circle, transmits rotary motion to the pump shaft crank 41 by means of the 90 ball bearing 33. It is clear that member 36 has no tendency to rotate except that due to friction of the cranks and this is resisted by tube 35 which is secured to plate 34. Member 36 will oscillate however and axis BB of 95 this oscillation is designed so that the tube is subjected to a natural and simple bending very slight in amount and only a fraction of the elastic limit of the tube.

The arrangement of the crank pins and 100 sockets in different transverse planes as shown in Figure 1 involves a certain amount of twisting strain and resulting friction between the member 36 and the rotating crank elements which, if desired, may be avoided 105 by arranging these parts concentrically so that they transmit power in the same transverse plane as shown in Figure 4. In this figure, the driving crank pin 38^a engages the member 36^a inside of and concentrically with 110 the crank stud 40^a which latter is encircled by the crank socket 41^a concentric therewith. If desired the eccentricity of the rotating load on the crank may be counterbalanced by eccentric weights 50 and 51 on the respective driving and driven shafts. It will be obvious that the relation of crank pins and 115 sockets may be reversed or varied if desired and in any case, the rotary crank axes may be made parallel with the shaft axis provided a double curve for tube 35 is found 120 unobjectionable.

It is obvious that oscillation of piece 36 may be accomplished in other ways such as by a cam for instance, and that this oscillating motion may be changed to rotary motion by external and internal gears or many other means, or to reciprocating motion in case it is desired to use a reciprocating pump instead of a rotary pump.

Shaft 37 is connected to the motor by the friction clutch 42 which may be any suitable form of friction clutch. The primary purpose of this is to limit the pressure in the condensing chamber as hereafter explained. It will be noted, however, that tube 35 is subjected to the torque due to the friction of the crank pins, and clutch 42 will prevent any excessive strain such as might be developed, as for instance, if some part of the mechanism should jam, or if the pump should suddenly suck a large quantity of liquid instead of gas.

The evaporator 29 is a copper vessel bolted to the condenser 13 and base casting 11, forming a unit with them. It contains the float 43 actuating the inlet valve 44 whereby fresh liquefied refrigerant is admitted to take the place of that evaporated. The refrigerant is preferably ethyl chloride. The float, which in this case is shown of cork, but may be constructed in other ways, has its buoyancy so proportioned to the size of the valve 44 that flotation will close the valve 44 against any usual pressures in the condenser, but not against an abnormal pressure. This valve thus becomes also a safety valve preventing any excessive pressure from generating in the condenser and eliminating the necessity of a pressure switch to cut out the motor.

Owing to the fact that normally, even when the machine is idle, the pressure in the evaporator is less than in the condenser, glycerine will from time to time flow from the pump in small quantities to the evaporator. Provision must, therefore, be made for returning this glycerine to the condenser. This is accomplished by providing a second float, 45, which is of buoyancy proportioned to its load so that it floats in glycerine but sinks in the liquid ethyl chloride. This float carries the tube 46 open at the bottom and entering the exhaust port 47. As glycerine accumulates it raises this float forcing the tube 46 further into the port 47 thereby throttling the suction on the gas until glycerine is sucked through the suction pipe into the pump and discharged into the condenser.

The refrigerating machine is attached to any suitable refrigerator 10 by cutting a hole in the top of the refrigerator through which the evaporator 29 projects. A brine tank 48 may be then slipped over the evaporator and held in place by the bayonet catch and slot 49. While the machine may be operated without the brine tank a more even temperature can be maintained in the ice box by its use as the brine supplies a reserve of cold to more quickly compensate the temperature when doors are opened, etc. A compartment 50 may be provided for the reception of trays containing water to be frozen.

A thermostatic electric switch (not shown as it is common in the art) controls the

motor starting it when the temperature in the box gets too high and stopping it when sufficiently low.

The device operates as follows:

The rotary pump applies suction to the evaporator creating a partial vacuum. This causes the ethyl chloride therein contained to boil lowering its temperature and causing it to absorb heat from the brine and, through it, from the ice box.

The gas drawn off from the evaporator is compressed in the pump and becomes heated. It is discharged hot and under pressure into the condenser where its heat is absorbed by the air cooled condenser walls and it liquefies, settling into the bottom of the condenser, and overflowing into the evaporator where it is again available for evaporation as before.

Other refrigerating agents and other lubricants can be used instead of ethyl chloride and glycerine as can other materials in the construction of the device. Likewise the transfer of power to within the enclosed vessel may be effected in many other ways than that shown in the preferred form. I therefore do not limit myself to the construction here shown but reserve the right to embody this invention in any other way which lies within the spirit of the invention and the scope of my claims.

While the apparatus may be constructed of any desired size and refrigerating capacity, it will be found that one somewhere around twice the dimensions shown in the original drawings forming part of this application will be of sufficient capacity for an ordinary small refrigerator. In such a device the motor may be about a quarter horse power rotating say 1700 revolutions per minute. The axis of the crank pins for transmitting the power from the motor to the compressor may have an eccentricity of say three-eighths inch giving a crank throw of three-quarters inch. With ethyl chloride as the refrigerant, the pressure maintained in the condenser may be about 40 pounds, float 43 and valve 44 being designed to withstand substantially that pressure. At such pressure the ethyl chloride will condense at about 130° Fahrenheit, thus giving a reasonable temperature drop and effective cooling for the outside air even in hot summer weather. The friction coupling 42 may be set to slip when the internal pressure against which the pump works is considerably above the working pressure of 40 pounds, the load required for slip being in such case a back pressure of say 90 to 100 pounds.

I claim:

1. An evaporating and condensing system for a volatile liquid, comprising a container having all exterior seams and openings fitted with closures secured gas-tight by sealed joints between surfaces which are

immovable during operation of the device and one of said closures being flexible; said container comprising interiorly an evaporating chamber and a condensing chamber with interiorly communicating conduits for circulation of fluid, one of said conduits being for flow of fluid from the evaporating chamber to the condensing chamber and another conduit for return of fluid from the condensing chamber to the evaporating chamber, in combination with a compressor pump located in the condensing chamber having its intake through said suction conduit, means for actuating said pump by non-rotary motion of a movable element carried by said flexible closure, an outlet valve located in said return conduit controlled by the buoyancy of a float in the vaporizable liquid in the evaporating chamber so as to vent the condensing chamber into the evaporating chamber when the pressure in the former exceeds a predetermined limit, and means for driving the compressor including a friction coupling adapted to slip in case the resistance and back pressure on the compressor becomes abnormally high.

2. An evaporating and condensing system for a volatile liquid, comprising a container having all exterior seams and openings fitted with closures secured gas-tight by sealed joints between surfaces which are immovable during operation of the device and one of said closures being flexible; said container comprising interiorly an evaporating chamber and a condensing chamber with interiorly communicating conduits for circulation of fluid, one of said conduits being for flow of fluid from the evaporating chamber to the condensing chamber and another conduit for return of fluid from the condensing chamber to the evaporating chamber, in combination with a compressor pump located in the condensing chamber having its intake through said suction conduit, means for actuating said pump by non-rotary motion of a movable element carried by said flexible closure, an outlet valve located in said return conduit controlled by the buoyancy of a float in the vaporizable liquid in the evaporating chamber so as to vent the condensing chamber into the evaporating chamber when the pressure in the former exceeds a predetermined limit.

3. An evaporating and condensing system for a volatile liquid, comprising a container having all exterior seams and openings closed by sealed joints between surfaces which are relatively immovable during operation of the device, said container comprising interiorly an evaporating chamber and a condensing chamber with interiorly communicating conduits for circulation of fluid, one of said conduits being for flow of fluid from the evaporating chamber to the condensing chamber and another con-

duit for return of fluid from the condensing chamber to the evaporating chamber, a rotary compressor located in the condensing chamber having its intake through said suction conduit and an outlet valve located in said return conduit controlled by the buoyancy of a float in the vaporizable liquid in the evaporating chamber adapted to vent the condensing chamber into the evaporating chamber when the pressure in the former exceeds a predetermined limit.

4. An evaporating and condensing system for a volatile liquid, comprising a container having all exterior seams and openings closed by sealed joints between surfaces which are relatively immovable during operation of the device, said container comprising interiorly an evaporating chamber and a condensing chamber with interiorly communicating conduits for circulation of fluid, one of said conduits being for flow of fluid from the evaporating chamber to the condensing chamber and another conduit for return of fluid from the condensing chamber to the evaporating chamber, a rotary compressor located in the condensing chamber having its intake through said suction conduit and an outlet valve located in said return conduit controlled by the buoyancy of a float in the vaporizable liquid in the evaporating chamber adapted to vent the condensing chamber into the evaporating chamber when the pressure in the former exceeds a predetermined limit, in combination with means for driving the compressor including a friction coupling adapted to slip in case the resistance and back pressure on the compressor becomes abnormally high.

5. A refrigerating apparatus comprising an evaporating chamber, a condensing chamber, a compressing pump, having conduit connections for sucking fluid from the evaporating chamber and compressing it in the condensing chamber, an overflow return conduit from the condensing chamber to the evaporating chamber, a supplemental suction conduit for drawing lubricating liquid from the bottom of the condensing chamber into the compressor and means for drawing lubricating fluid from the bottom of the evaporating chamber to the main intake of the compressor, said means comprising a valve having a tubular stem adapted to variably throttle the intake of said main suction conduit, the lower end of said tubular stem being in communication with the bottom of the evaporating chamber and a float adapted to lift said tube and valve to increase throttling of the suction intake when the lubricant in the evaporating chamber exceeds a predetermined depth.

6. A refrigerating apparatus comprising an evaporating chamber, a condensing chamber, a compressing pump and suction conduit for pumping vaporized refrigerant

- from the evaporating chamber to the condensing chamber and a valve controlled passage for return of fluid to the evaporating chamber, in combination with means for applying non-volatile lubricating spray to the intake of said pump, said means comprising a valve having a perforated stem projecting into the suction passage leading from the evaporating chamber to the compressor and having its lower end extending into a body of fluid lubricant.
7. A refrigerating apparatus comprising an evaporating chamber, a condensing chamber, a compressing pump and suction conduit for pumping vaporized refrigerant from the evaporating chamber to the condensing chamber and a valve controlled passage for return of fluid to the evaporating chamber, in combination with means for applying non-volatile lubricating spray to the intake of said pump, said means comprising a valve having a perforated stem projecting into the suction passage leading from the evaporating chamber to the compressor and having its lower end extending into a body of fluid lubricant, and means controlled by the level of the lubricant to vary the degree of throttling of said suction passage by said valve and tubular stem.
8. A refrigerating apparatus comprising an evaporating chamber, a condensing chamber, a compressor located in said condensing chamber, and suitable conduit connections for pumping evaporated refrigerant from the former to the latter and a valve controlled passage for return of fluid to the evaporating chamber, in combination with a motor outside said chamber and means for transmitting power from the outside motor to the interior compressor, said means including a power shaft extending freely through an opening in a wall of the condensing chamber, and means for transmitting the rotary motion of said motor shaft to the compressor shaft, said means including an imperforate power transmitting member, means on the motor shaft for driving said intermediate member in a circular path without rotating it and a flexible closure for sealing said imperforate member over said shaft opening and over the portion of said shaft extending inside said wall through said opening.
9. A refrigerating apparatus comprising a suitable support, a container for the refrigerant secured to and depending from said support, a cooling and condensing chamber secured to the upper side of said support having cooling projections on the outside surface thereof and an outside wall enclosing the same to form longitudinal passages for the cooling air, an electric fan motor at one end of said cylinder, end walls for said condensing chamber comprising plates secured gas-tight on the ends thereof, a compressor mounted on the inner face of one of said plates, power transmitting means mounted in and extending from the inner face of the opposite plate including suitable bearings formed on said plate, a rotatable shaft mounted in said bearings and extending through an exterior opening in said plate and a gas-tight closure for said exterior opening and shaft, said closure including a flexible element and an imperforate power transmitting member secured gas-tight to a movable portion of said flexible element, means on the driving shaft engaging an outwardly presented portion of said power-transmitting member to move the same without rotating it, and means on the compressor shaft engaging an inwardly presented portion of said member to be rotated by the non-rotary movement of the latter.
10. A refrigerating apparatus comprising a suitable support, a container for the refrigerant secured to and depending from said support, a cooling and condensing chamber secured to the upper side of said support having cooling projections on the outside surface thereof and an outside wall enclosing the same to form longitudinal passages for the cooling air, an electric fan motor at one end of said cylinder, end walls for said condensing chamber comprising plates secured gas-tight on the ends thereof, a compressor mounted on the inner face of one of said plates, power transmitting means mounted in and extending from the inner face of the opposite plate including suitable bearings formed on said plate, a rotatable shaft mounted in said bearings and extending through an exterior opening in said plate and a gas-tight closure for said exterior opening and shaft, said closure including a flexible element and an imperforate power transmitting member secured gas-tight to a movable portion of said flexible element, means on the driving shaft engaging an outwardly presented portion of said power-transmitting member to move the same without rotating it, and means on the compressor shaft engaging an inwardly presented portion of said member to be rotated by the non-rotary movement of the latter.
11. An evaporating chamber and a condensing chamber containing a body of liquid refrigerant and also a body of liquid lubricant of greater specific gravity than said refrigerant, in combination with means for pumping fluid from the evaporating chamber into the condensing chamber; a valve controlling the passage for return flow of fluid from said condensing chamber to said evaporating chamber; and a throttle element having a tubular stem adapted to project into and variably throttle the suction passage to the compressor at one end and having its inlet end below the level of said lubricant and a float having its buoyancy proportioned to its load so that it floats upon

- 6 and is controlled by the level of said lubricant.
12. An evaporating chamber and a condensing chamber containing a body of liquid refrigerant and also a body of liquid lubricant of greater specific gravity than said refrigerant, in combination with means for pumping fluid from the evaporating chamber into the condensing chamber; a valve controlling the passage for return flow of fluid from said condensing chamber to said evaporating chamber; a float buoyed by the refrigerant and having its lifting power proportioned to said valve so as to with- 70 stand a desired predetermined pressure in said condensing chamber but yielding in response to greater pressure; and a throttle element having a tubular stem adapted to project into and variably throttle the suc- 75 tion passage to the compressor at one end and having its inlet end below the level of said lubricant and a float having its buoyancy proportioned to its load so that it floats upon and is controlled by the level of 80 said lubricant.
13. A chamber containing gas hermetically sealed against escape to the exterior air, and exterior and interior mechanisms, one driving and the other driven thereby, in combination with means for transmitting 85 motion between said mechanisms through a wall of said chamber, said means including a shaft having one end extended inwardly through an opening in the chamber 90 wall and provided with a crank on the inner end thereof, a crank on the shaft of said interior mechanism in alignment with said first mentioned crank, an imperforate, non-rotating member for transmitting the 95 motion of said shaft, and a flexible tube secured gas-tight over said shaft opening and also to said intermediate member, the axis of the aligned crank pins being inclined to the axis of the shafts on which 100 they are mounted and the plane of the intermediate member correspondingly inclined so that said flexible tube bends by the continuous curve in one direction from the fixed to the movable end thereof. 105
14. A chamber containing gas hermetically sealed against escape to the exterior air, and exterior and interior mechanisms, one driving and the other driven thereby, in combination with means for transmitting 110 motion between said mechanisms through a wall of said chamber, said means including a shaft having one end extended inwardly through an opening in the chamber wall and provided with a crank on the inner 115 end thereof, a crank on the shaft of said interior mechanism in alignment with said first mentioned crank, an imperforate, non-rotating member for transmitting the motion of said shaft and a deeply corrugated thin metal tube encircling said shaft and 120 having its ends rigidly secured gas-tight, one end around said shaft opening and the other end to said intermediate member, the axis of the aligned crank pins being inclined to the axis of the shafts on which 70 they are mounted and the plane of the intermediate member correspondingly inclined so that said flexible tube bends by the continuous curve in one direction from the fixed to the movable end thereof. 75
15. In an apparatus utilizing cyclic expansion and compression of a gas, including a gas containing chamber, a compression chamber and means for transmitting power through a wall of said apparatus, said means including a deeply corrugated thin metal tube having one end secured gas-tight around an opening in the wall of said compression chamber, and an imperforate non-rotating power transmitting member 80 secured gas-tight in the other end of said tube. 85
16. In an apparatus utilizing cyclic expansion and compression of a gas, including a gas containing chamber, a compression 90 chamber, a pressure translating mechanism located in one of said chambers and conduits for flow of fluid in a cyclic path through said gas containing chamber, mechanism and compression chamber; and 95 means for transmitting power through a wall of said apparatus, said means including a non-rotating flexible member secured gas-tight over an opening through said 100 wall. 105
17. In an apparatus utilizing cyclic expansion and compression of a gas, including a gas containing chamber, a compression chamber, a pressure translating mechanism located in one of said chambers 110 and conduits for flow of fluid in a cyclic path through said gas containing chamber, mechanism and compression chamber; and means for transmitting power through a wall of said apparatus, said means including a deeply corrugated thin metal tube having one end secured gas-tight around an opening in the wall of said compression chamber, and an imperforate non-rotating power transmitting member secured 115 gas-tight in the other end of said tube. 120
18. In an apparatus utilizing cyclic expansion and compression of a gas, including a gas containing chamber, a compression chamber and means for transmitting power through a wall of said apparatus, said means including a non-rotating flexible member secured gas-tight over an opening through said wall. 125
19. An apparatus for compressing gas including a gas containing chamber, a compression chamber, a compression mechanism located in one of said chambers and conduits for flow of fluid in a cyclic path through said gas containing chamber, said 130

- compression mechanism and said compression chamber; and means for transmitting motion between the interior and exterior of said apparatus, said means including a non-
5 rotating flexible member sealed gas-tight over an opening through a wall of one of said chambers.
20. An apparatus for compressing gas including a gas containing chamber, a compression chamber, a compression mechanism located in one of said chambers and conduits for flow of fluid in a cyclic path through said gas containing chamber, said compression mechanism and said compression chamber; and means for transmitting motion between the interior and exterior of said apparatus, said means including a deeply corrugated thin metal tube having one end secured gas-tight around an opening in the wall of said compression chamber;
- 10 15 20
- ber, and an imperforate non-rotating power transmitting member secured gas-tight in the other end of said tube.
21. In a power transmitting joint for gas compressors, the combination of a pump; 25 a motor; a driving connection between the motor and the pump comprising a joint; a bellows diaphragm sealing the joint; and a movable member extending from the motor through the diaphragm to the pump for 30 conveying the movement of the motor to the pump; the bellows being arranged to extend toward the high pressure side of the joint so that the compression takes effect on the exterior of the bellows, for the purpose described.
- Signed at New York city in the county of New York and State of New York this 25 day of February A. D. 1920.

BRADFORD B. HOLMES.
